(57) **CLAIM**

The ornamental design for a card case.

DESCRIPTION

FIG. 1 is a perspective view showing the top, right and front views of the inventive card case.

FIG. 2 is a perspective view showing the top, right and front views of the inventive card case, with cards shown in an environment of use, shown with the elastic band off and the case partially open.

FIG. 3 is a top view of FIG. 1.

FIG. 4 is a bottom view of FIG. 1.

FIG. 5 is a right view of FIG. 1.

FIG. 6 is a left view of FIG. 1.

FIG. 7 is a back view of FIG. 1; and,

FIG. 8 is a front view of FIG. 1.

The evenly dashed broken lines depict portions of the article and form no part of the claim. The dash-dot-dash broken lines depict environment and form no part of the claim.

1 Claim, 8 Drawing Sheets
